Des. 234,103
Patented Jan. 21, 1975

234,103

COMBINED CYCLE SEAT AND FENDER

Michael W. Hanagan, Somers, Conn., assignor to Corbin Gentry, Inc., Somersville, Conn.

Filed Sept. 13, 1973, Ser. No. 397,133

Term of patent 14 years

Int. Cl. D12—11

U.S. Cl. D6—48.1

FIG. 1

FIG. 2

FIG. 3

FIG. 5

FIG.6

FIG.4

FIG. 1 is a perspective view of a combined cycle seat and fender showing my new design;

FIG. 2 is a side elevational view thereof;

FIG. 3 is a rear elevational view thereof;

FIG. 4 is a bottom plan view thereof;

FIG. 5 is a front elevational view thereof; and

FIG. 6 is a top plan view thereof.

The broken lines shown on the seat in FIGS. 1, 2, 5 and 6 represent stitching.

I claim:

The ornamental design for a combined cycle seat and fender, as shown and described.
